UNITED STATES PATENT OFFICE.

HENRY A. SMITH, OF LOS ANGELES, CALIFORNIA.

PADLOCK.

SPECIFICATION forming part of Letters Patent No. 710,722, dated October 7, 1902.

Application filed October 5, 1901. Serial No. 77,711. (No model.)

To all whom it may concern:

Be it known that I, HENRY A. SMITH, a citizen of the United States, residing at Los Angeles, in the county of Los Angeles and State 5 of California, have invented new and useful Improvements in Padlocks, of which the following is a specification.

This invention is applicable to padlocks adapted for any of the uses to which such 10 locks may be applied. It is specially designed, however, for car and switch locks.

A feature in padlocks ordinarily employed for locking railway cars and switches is that the same may be unlocked without a key by 15 concussion—that is to say, trainmen and others acquainted with the fact are accustomed to readily open such locks by applying pressure to the hasp and at the same time striking the case of the lock in such a way 20 that the inertia of the members of the lock will cause the catch to withdraw from the hasp, thus allowing the hasp to open.

One object of my invention is to construct a lock of very simple character which can- 25 not be opened by any such means.

Another object of the invention is to construct a padlock of few parts of simple character which affords an opportunity for considerable variation in the keys for different 30 locks.

The accompanying drawings illustrate my invention.

Figure I is a view of a lock embodying my invention, one plate of the case or frame of 35 the lock being omitted to expose the interior parts and portions of the hasp and key being shown in section. Fig. II is a section on line II II, Fig. I, looking in the direction of the arrows. Fig. III is a detail elevation of the 40 stationary and sliding wards. Fragments of the frame of the lock are shown in section on line III III, Fig. I. The keypost is also shown. Fig. IV is a plan section on line IV IV, Fig. III. Fig. V is a detail of the side of 45 the wards reverse to that shown in Fig. III. Fig. VI is a view of one side of the key detached. Fig. VII is a fragmental view illustrating the other side of the key.

1 designates the frame of the lock; 2, a hasp, 50 and 3 a catch, respectively furnished with engaging faces 4 5, which are oblique to the path of the catch. The bottom of the recess

forms a shoulder and is inclined downwardly and outwardly, so that its remote or outer portion is deeper than its near or inner portion, and the end of the catch is inclined inwardly and upwardly on its under surface or is formed substantially hook-shaped by extending its tip below the bottom of the main portion a distance equal to the 55 depth of the inclination of the bottom of the recess to correspond and engage with the shoulder or inclined bottom of the recess. The catch moves in a straight line at substantially a right angle to the free end of the 60 hasp, and in order to permit its tip or hook engaging with or being disengaged from the shoulder or bottom of the recess of the hasp the end of the hasp must be forced inward a distance equal to the depth of the incline of 65 70 the bottom of the recess, for the reason that the tip of the catch must move back and forth in a straight line. If desired, the inward movement of the hasp may be limited, as by means of stops formed on the hasp above 75 the recess, which will engage with the top of the frame and prevent the further inward movement of the hasp.

6 designates means to yieldingly hold the catch 3 in locking position. The catch 3 slides 80 in the direction indicated by the double-headed arrow and is held in place and guided by a rectilinear way which is formed by the frame 1 of the lock and studs 7 8, adapted for that purpose.

9 designates means for yieldingly holding the hasp 2 open in the position indicated by dotted lines in Fig. I. The hasp is mounted in the frame by means of a pivot 10 in the ordinary way, and the spring 6 yieldingly 85 holds the catch in position, with its engaging face 5 in the path of the engaging face 4 of the hasp.

11 designates a stationary ward furnished with a passage 12 for a portion 13 of a key 14, 90 which is constructed to engage the arm 15 of the catch 3 to withdraw the catch from the hasp. The arm extends downwardly from the under side of the catch between the pins 7 and 8, which project out from one side of 95 the casing and support the catch and act as stops to limit its endwise movement. The tip of the arm is rounded in front for engagement by the key in throwing it back. The 100

- rear face of the arm is recessed longitudinally for the reception of the free end of the spring 6. The arm is of such width that it extends beyond one side of the catch far enough to engage with one side *b* of the casing and hold the catch substantially midway between the sides of the casing, a lug 22 on the other side of the catch engaging with the other side *a* of the casing.
- 10 16 designates a sliding ward, and 17 means for yieldingly holding the sliding ward in position to guard the key-passage 12 of the stationary ward 11 and furnished with a key-receiving portion 18 to be engaged by a portion 19 of the key 14, which is constructed to enter the case through the usual keyhole (not shown) and to turn on the key-post 20 and arranged to slide the sliding ward when the key is rotated and remove said sliding ward from the 20 path of the catch-operating portion 13 of the key. The beveled portion 18 of the sliding ward extends out of line of the passage 12 of the stationary ward, and the key is furnished with a forward projection 19 to engage the 25 beveled portion 18 before the catch-engaging portion 13 of the key has come into contact with the sliding ward 11.
- 22 designates a lug on one side of the catch to move inside the frame 1 of the lock to engage the side member *a* of said frame to thereby hold the catch in position.
- The hasp and catch are rounded at their contacting ends to allow the hasp to pass the catch readily in the usual way.
- 30 23 designates the eye or recess in the end of the hasp to receive the catch.
- The stationary ward 11 may be formed on or connected with the frame in any way. In the drawings it is shown connected with the 40 frame by means of a post 24 and by insertion into grooves 25 (shown only in dotted lines) in the sides *a* *b* of the frame.
- When the hasp is inserted into the frame and the catch is inserted into the recess 23, 45 the pressure of the spring 9 on the end 26 of the hasp draws the hasp outward in the way usual with spring-padlocks, and by reason of the oblique character of the engaging faces 4 and 5 of the hasp and catch the catch is retained in its locking position. The spring 6 50 forcibly holds the catch in such position. If an attempt is made to open the lock by concussion, the action is as follows: Any pressure applied to move the hasp out will force the oblique faces together, so as to prevent 55 the catch from withdrawing from the hasp. To unlock the lock with a key, the hasp is pressed in while the key is rotating. The forward projection 19 of the key first acts upon the beveled portion 18 of the sliding ward, and 60 thereby forces the sliding ward back out of the path of the catch-operating portion 13 of the key, allowing said catch-operating portion 13 to pass through the passage 12 of the ward 65 therefor and to act upon the arm 15 of the catch to slide the catch out of the way. When the catch has been thrown sufficiently,

the hasp is allowed to withdraw, whereupon the key passes the arm 15 and allows the catch to return to its locking position to receive and hold the hasp when the same is again inserted. In Fig. I the curved dotted arrow indicates the movement of the catch-operating portion 13 of the key.

70 27 designates a guard-ring, any number of which may be applied in the ordinary way to vary the form of the key. Additional variations are provided for by the stationary ward 11, the key-passage 12 through which may be varied in size and position, and the catch-operating portion 13 of the key being necessarily of such a length that it will not pass the sliding ward 11 unless the same is forced back.

75 Many variations of the invention will readily suggest themselves to any one versed in this art, and no attempt to illustrate the various modes of carrying out my invention is made in this application, and I do not limit myself to any specific form.

80 What I claim, and desire to secure by Letters Patent of the United States, is—

85 1. In a lock, a casing, a curved hasp pivotally secured at one end to the casing and having a forwardly and downwardly inclined recess at the other end and a straight catch arranged to move in a right line substantially radially relatively to the pivot-point of the hasp and at right angles to the free end of the hasp, the outer end of the catch being substantially hook-shaped and adapted to be 90 moved into and out of engagement with the recessed portion of the hasp.

95 2. In a lock, a casing, a hasp pivotally secured thereto at one end and having its end provided with an inclined shoulder and with 100 a stop, the outer portion of said incline being deeper than the inner portion, and a straight catch movable in a straight line into and out of engagement with said shoulder, the tip of the catch being inclined on its under surface and 105 extending below the bottom of the main portion to form a hook, and the stop on the hasp being located a sufficient distance above the shoulder to permit of the free end of the hasp being forced into the casing beyond its normal position, equal to the length of said extension of the tip of the catch.

110 3. In a lock, a casing provided with three pins, a hasp pivotally secured to the casing, the free end of which is shouldered and the 115 other end extends beyond the pivot, a longitudinally-movable catch on two of the pins, one side of which is provided with a lug for engaging with one side of the casing and the under side is provided with an arm between 120 the lugs, one side of said arm engaging with the other side of the casing, whereby the catch is held substantially midway between the sides of the casing, and two springs on the third pin, one of which engages with the extension of the hasp and the other one engages with the arm of the catch adjacent to one side of the casing.

125 4. A lock furnished with a catch, means for

yieldingly holding the catch in locking position, a stationary ward, a sliding ward, means for yieldingly holding the sliding ward in position to guard the key-passage of the stationary ward and furnished with a key-receiving face, and a key to operate said catch constructed to slide the sliding ward and to then pass the stationary ward to move the catch.

5. In a lock, a stationary ward and a sliding ward constructed to extend across the path of the key, a catch, and a key constructed to move the sliding ward, pass the stationary ward, and move the catch.

6. A lock comprising a catch; a stationary ward having a passage for a portion of a key; a sliding ward constructed to close said pas-

sage and furnished with a beveled face extending out of line with said passage; means for yieldingly holding the sliding ward to close said passage; and a key furnished with 20 a portion to operate the sliding ward and with another portion to pass through said passage to operate the catch of the lock.

In testimony whereof I have signed my name to this specification, in the presence of 25 two subscribing witnesses, at Los Angeles, California, this 30th day of September, 1901.

HENRY A. SMITH.
